UNITED STATES PATENT OFFICE

MALCOLM A. NEAL, OF SAN FRANCISCO, CALIFORNIA, ASSIGNOR TO AERIAL ADVERTISING COMPANY, INC., OF SAN FRANCISCO, CALIFORNIA, A CORPORATION OF NEVADA

AERIAL SIGN

Application filed August 20, 1928. Serial No. 300,721.

My invention relates to advertising displays supported by balloons or kites, and its broad purpose is to provide a sign of minimum weight which will withstand the large 5 stresses due to wind pressure.

An object of my invention is to provide an improved sign foundation made from lines or cords, and a method of making the same, with a maximum of accuracy and a 10 minimum difficulty from tangling of the lines.

Another object of my invention is to provide such a sign, the lines of which are not subject to chafing.

My invention possesses other objects and 15 valuable features, some of which will be set forth in the following description of my invention which is illustrated in the drawings forming part of the specification. It is to be understood that I do not limit myself to 20 the showing made by the said description and drawings, as I may adopt varying forms of my invention within the scope of the claims.

Referring the drawings:

25 Fig. 1 is an elevation of a frame used in the building of the sign of my invention, with a sign thereon in the course of construction.

Figs. 2, 3 and 4 are detail views on an enlarged scale, illustrating the transfer of a 30 hitch from the transverse to the longitudinal line of the foundation network, and the overhand knot for finally securing the connection.

The use of balloon or kite supported signs 35 is of constantly growing importance in modern advertising. Such signs to be effective must be of large area, and at the same time must be very light. The stresses due to wind pressure are large, and whipping in high 40 winds causes rapid wear. The requirement of light weight and low wind resistance has led to the use of a fish-net foundation, with letters or other devices to be displayed cut from silk or other light fabric and stitched to 45 the netting.

This construction leaves much to be desired, for the net must be of small mesh to bring the lines where they are needed, and many more lines must be used than are actually necessary for strength. The lines sel-

dom coincide accurately with the edges of the letters, with the result that these edges are often free to whip in the wind and tear loose, and the irregular form of the letters causes oblique stresses which result in distortion of the sign. In my invention these troubles are avoided.

In broad terms, my invention comprises a foundation network in which the individual lines correspond to the edges of the applied device, which is formed of fabric in the usual manner. The edges are hemmed, and stitched around the lines, eliminating the trouble from whipping. Individual lines are used for each series of edges alined across the sign surface, and the intersecting lines are knotted in such a manner that the intersections may be located with great accuracy, the completed knot being firm and free from danger of slipping and chafing. There is perfect freedom of selection in the placing of these lines, and the number of transverse lines in the successive rows of characters may be changed, by providing lines of opposing pull to balance out the oblique components.

The preferred embodiment of my invention may be best described by reciting in detail the method of construction.

A frame 6 is erected against a wall on which is the lay-out of the sign to be built, and extending diagonally upward and away from the frame, in the same plane, is a beam 8. Pins 9 on the frame carry spars 11 and 12 which form the upper and lower edges of the sign, and hemp lines 13 and 14 attached to the ends of the spars complete the outline.

Longitudinal lines 15, positioned to correspond with the longitudinal edges of the characters to be displayed are next stretched from pins 16 in one edge of the frame, passing over other pins 17 in the beam 9, and terminating in the weights 18 which keep the lines taut.

Lines 21, corresponding to the transverse edges of the letters, are next attached to the upper spar, and tied at each intersection with the lines 15. The junction must be accurately spaced, and when complete must not be subject to slipping along either line. Owing to the great length—often 50 feet or more—

of the longitudinal lines, it is not practical to make the knots in them, and all tying must be done with the short transverse lines. Ordinary knots made in this manner will slip 5 along the longitudinal line. This is prevented as follows:

A clove hitch is thrown in the line 21 about the line 15 as shown in Fig. 2. This will slip along the line 15, and advantage is taken 10 of this to position the intersection accurately in the horizontal direction. A strong pull on the line 21 then causes it to straighten and transfers the hitch to the line 15 as shown in Fig. 3. The intersection may then be 15 slipped into position in the vertical dimension, and a single overhand knot then tied about the hitch to prevent further slippage, as shown in Fig. 4.

The longitudinal lines are shortened by 20 transferring the clove hitch thereto and the overhead knots are then tied in the vertical lines to shorten the same, and therefore to prevent the displacement of intersections already tied by the formation of succeeding 25 knots, the tying is started at the fixed end of the upper longitudinal line, taking each intersection successively down and across the frame. The weights 18 rise to yield the necessary slack in the longitudinal lines.

30 Diagonal lines may be started from any intersection, as is shown by the lines 22 comprising the edges of the letter A in the sign. When so started and terminated these lines do not introduce distorting pulls. In case 35 the transverse lines of a lower row of letters do not coincide in spacing with the upper row, however, and it is necessary to terminate a line or displace it to one side or the other, distorting pulls will be set up. This 40 is prevented by displacing the lines in pairs, thus counterbalancing the longitudinal component of the pull of a diagonal line 23 by an equal and opposite pull from another line 24, so that the resultant is a straight transverse 45 pull which is taken by the lines 25. It is also possible to obtain the same result by balancing the pulls of two slightly displaced lines 26 by that of a single line of greater slope 27. Where a line is terminated it is done as 50 is shown by using the two diagonal lines 28 whose opposing pulls are transmitted as a direct transverse stress to the line 29.

When all intersections have been tied the longitudinal lines are fastened to the hemp 55 line 14, and the transverse lines secured to the lower spar 12, thus completing the foundation net.

With the net thus formed, the device to be displayed is next applied. The characters 60 31 are cut from silk or other light fabric, and a narrow hem 32, perhaps $\frac{1}{2}$ inch wide, formed around the edge. The hem is secured to the lines by stitching and knotting at intervals, much as in quilting. The use of these 65 separate stitches 33 saves a fraction in weight,

and decreases the danger of a whole edge coming loose if a single thread breaks. Similar stitches 34 between the edges make the characters more secure. Stitches are preferably taken at each intersection of the foundation lines and at one or more points between. 70

The completed sign is both lighter and more permanent than the usual type. There are certain modifications which may be made in the construction without departing from my invention. Thus a diagonal terminating 75 at both ends in longitudinal or transverse character elements, as, for example, the cross bar of the letter N, need not necessarily have the usual line along the edge, especially if the character be relatively small. In general, however, the security given by the diagonal lines justifies their weight. 80

I claim:

1. A method of tying a long and a short 85 line which comprises throwing a clove hitch in the short line about the long line, tensioning the short line to transfer the hitch to the long line, and knotting the short line about the hitch.

2. A method of forming an accurately spaced connection between two intersecting 90 lines which comprises throwing a clove hitch in one line about the other, sliding said hitch into position on said second line, transferring said hitch to said second line by tension on said first line, sliding said hitch into position on said first line, and knotting said first line about said hitch. 95

3. A method of constructing a sign which 100 comprises stretching lines corresponding to each longitudinal element of the display, stretching lines corresponding to transverse elements of the display across said longitudinal lines, knotting each intersection of said 105 lines, forming in fabric the device of the display, and securing each edge of said device to its corresponding stretched line. 110

4. A method of sign construction comprising stretching a plurality of longitudinal 115 lines, crossing said lines with a plurality of transverse lines; tying each intersection by throwing a clove hitch in the transverse line about the longitudinal line, transferring said hitch to the longitudinal line by tension on the transverse line, and knotting the transverse line about said hitch; the ties being formed in regular succession along each longitudinal line, forming in fabric the device to be displayed, and stitching the edges of said fabric to corresponding lines. 120

5. A method of constructing a sign which 125 comprises stretching lines corresponding to each longitudinal element of the display, stretching lines corresponding to transverse elements of the display across said longitudinal lines, knotting each intersection of said lines, and securing the edges of the device to be displayed to their corresponding lines.

6. A method of sign construction compris- 130

ing stretching a plurality of longitudinal lines, crossing said lines with a plurality of transverse lines; tying each intersection by throwing a clove hitch in the transverse line about the longitudinal line, transferring said hitch to the longitudinal line by tension on the transverse line, and knotting the transverse line about said hitch; the ties being formed in regular succession along each longitudinal line, and securing the edges of the device to be displayed to their corresponding lines.

7. A sign having a foundation network comprising longitudinal lines, and a plurality of transverse lines secured thereto, said transverse lines being displaced in opposite directions to balance the longitudinal components of the stresses thereon.

In testimony whereof, I have hereunto set
20 my hand.
